WASH FOUNTAIN

Herman E. Heine, Milwaukee, Wis., assignor to
Bradley Washfountain Company, Milwaukee,
Wis., a corporation of Wisconsin

Application June 6, 1938, Serial No. 211,969

11 Claims. (Cl. 4—195)

The invention relates to wash fountains and more particularly to an arrangement for the conduction of the drainage water from the fountain and the supply of fresh water thereto.

Heretofore it has been customary to run the inlet water supply pipe directly through the drain passage and form one of the joints for said pipe in said passage which under certain conditions will permit drainage water finding its way into the supply water passing to the sprayhead or other point of use. Also where the drain passage is associated with a trap and the supply water comes through a passage in the trap, defective castings may permit the supply water becoming contaminated with water from the drain. In order to overcome the above mentioned difficulties the present invention has for its object to provide a supply and drainage arrangement whereby the supply water is separated from the drain water through an entirely separate passage and through an air space between the supply and drainage passages.

The invention further consists in the several features hereinafter set forth and more particularly defined by claims at the conclusion hereof.

In the drawings:

Fig. 1 is a vertical sectional view of a wash fountain provided with apparatus embodying the invention;

Fig. 2 is a detailed sectional view taken on the line 2—2 of Fig. 1;

Fig. 3 is a detailed elevation view of one of the parts of the drain fitting;

Fig. 4 is an enlarged view of parts shown in Fig. 1;

Fig. 5 is a detailed sectional view showing another modified form of the invention;

Fig. 6 is a vertical sectional view through a wash fountain provided with another form of the invention;

Fig. 7 is a sectional view showing certain modifications of the structure shown in Fig. 6;

Fig. 8 is a view similar to Fig. 7 showing another modification.

Referring to Fig. 1, the numeral 10 designates a basin which may be of circular, semi-circular, or other suitable form mounted on a support or pedestal 11.

A tubular sprayhead supporting member 12 having drain openings 13 in its lower end seats on a spud 14 mounted in a recessed opening 15 in the bottom of the basin. The member 12 supports a sprayhead structure 16 which may be similar to that shown in the prior U. S. Patent No. 2,085,824, dated July 6, 1937, and which is

designed to project a series of streams of water outwardly and downwardly into the basin.

A drain fitting 17 has a threaded opening 18 in its upper end engaging the lower threaded end of the spud 14, a circular chamber 19 formed in said upper end, a passage 20 offset from one side of said chamber and extending downwardly and provided with a threaded lower end 21 engaging a drain pipe 22. The bottom of the chamber 19 is provided with a threaded opening 23 concentric with the opening 18 and adapted to receive the lower end of a pipe or separator member 24 which extends up through the drain to a height somewhat above the height of the basin 10, so that water from the drain will be prevented from overflowing through said pipe even if the basin should become full of waste water.

It will be noted that passage 20 makes a curve from its point of connection with the chamber 19 to its lower end and that a boss 25 is formed on the wall of said passage in line with the opening 23 and adjacent a clearance space formed beneath the chamber 19. This boss 25 is provided with a threaded opening 26 adapted to receive the threaded plug 27 formed on the lower end 28 of an elbow fitting 28 which is provided with a side opening into which the pipe 29 is threaded and a top opening into which an upwardly extending supply pipe 30 is threaded. The pipe 29 may be supplied with tempered water through a suitable hand controlled mixing valve 31 which has a hot water connection 32 and a cold water connection 33 leading thereto. The pipe 30 leads directly to the sprayhead 16 and extends through the member 24 from which it is spaced by an air gap, said member 24 normally keeping the drain water from coming in contact with the inlet pipe connections including the pipe 30 and fitting 28, though if any drainage water should get through between the member 24 and the drain fitting 17, it will leak out to atmosphere and will not be subjected to any pressures which might tend to force it into the supply connections as has occurred where the supply pipe passes directly through the drain passage and has a joint or joints forming part of the wall of the drain passage.

In some instances the inlet water supply pipe comes from above the basin and through a valve located below the basin and then up to the sprayhead, and in such instance the inlet connections may be arranged as shown in Fig. 5 and associated with the drain fitting 17. As herein shown in place of the elbow fitting 28, I use a special fitting 34 having a partition 35 and

provided with threaded openings 36, 37, 38, and 39. The inlet pipe 40 from an overhead supply extends down to the partition 35 and has threaded connection with the threaded opening 38. The water then passes through the space 41 to the pipe 42 connected with the threaded opening 37 by which it is lead through a valve such as a foot controlled valve, for example of U. S. Patent No. 2,085,824 of July 6, 1937, and returns by way of pipe 43 connected with the threaded opening 36 to the space 44 from which it passes upwardly to the sprayhead through the pipe 45 connected to the threaded opening 39. It is to be noted that the pipe 45 extends up through the separator 15 pipe 24 similar to the pipe 30 of the first described construction and is separated from pipe 24 by an air gap. The fitting 34 has a threaded boss 46 adapted to engage in the threaded opening 26 in the drain fitting 17.

20 In those instances where it is desirable to associate a trap directly with the drain, the structure shown in Fig. 6 may be used. As shown the lower threaded end of the spud 15 connects with the threaded end 47 of a special trap fitting 48 which 25 has the chamber 48' at its upper end connected by an offset passage 49 to the trap or U-shaped portion 50 which connects by a relatively straight passage 51 with an outlet passage 52, the passages 52 and 51 also connected with a vent passage 53 30 having a threaded outlet 54 which is connected to an upwardly extending vent pipe 55.

The water supply connection leading to the sprayhead, such as 16 of Fig. 1, is formed in this instance between the pipe 55 and a pipe 56 concentric therewith and connected to a manifold 57 whose lower end 58 is sweated to said pipe 55 and has a laterally disposed inlet pipe 59 connected thereto. The supply connection thus formed is completely separated from the drain passage including the member 12 through which it projects by a pipe or separator member 60 which extends up to a height above the top of the basin 10 similar to the pipe 24 of the first described construction and at its lower end threads into a nut or 45 threaded plug member 61 which engages the opening 62 in the wall 63 of the fitting 48 which opening is made large enough to allow the manifold 57 to pass through, so that the vent pipe 55 may be screwed into place.

50 With this construction the inlet pipe is separated from the drain by the pipe 69 and an air space and has a fluid tight connection with the vent pipe 55.

Where it is not desired to mount the inlet manifold directly on the vent pipe, the modification shown in Fig. 7 may be used wherein the vent pipe 55' is similar to the vent pipe 55 and the supply connection is formed by a manifold 57' and concentric pipes 58' and 56' in threaded engagement 55 therewith, said manifold having the supply pipe 59' connected thereto, the pipes 55', 58', and 56' and the manifold 57' adapted to be substituted for the pipes 55, 56 and manifold 57 shown in Fig. 6, so that the inlet connection including pipes 58' 65 and 56' passes up through the pipe 60. It is to be noted that in this modified form the inlet connection is separate from the drain passage and from the vent associated with the trap in said passage.

70 In those instances where an upwardly extending vent is provided associated with a trap 48 and the supply comes from above the basin, the details of the inlet connections arranged as shown in Fig. 8 wherein the numeral 55' designates the vent pipe, and 64 an annular manifold surround-

ing said vent pipe and having pipes 65, 66, and 67 in threaded engagement therewith, the pipes 65 and 66 cooperating with the manifold 64 to form an annular passage for conducting the inlet water downwardly and having a threaded outlet 68 from which the water may be led through a control valve (not shown) and then conducted to the inlet 69 of an annular passage formed by the pipes 66 and 67 and the manifold 64 whereby the water is carried to the sprayhead such as the sprayhead 16 of Fig. 1, it being noted that the outer pipe 67 is of a diameter to fit within the pipe 60 of Fig. 6 and be spaced therefrom.

I desire it to be understood that this invention is not to be limited to any particular form or arrangement of parts except in so far as such limitations are included in the claims.

What I claim as my invention is:

1. In a wash fountain, the combination with a basin having a drain passage, spraying means supported above the basin for directing water toward the outer portion of the basin, a fresh water supply connection for said spraying means including a conduit, and a member extending up through said drain passage and through which said conduit extends in spaced relation and by which it is separated by said member and by an air space from drain water in said passage.

2. In a wash fountain, the combination with a basin having a drain passage, spraying means supported above the basin for directing water toward the outer portion of the basin, said drain passage including a fitting having a pipe mounted thereon and extending up through the drain passage to a position above the top of the basin to form an annular passage, and a fresh water supply connection for said spraying means including a conduit extending through said pipe and spaced therefrom by an air space.

3. In a wash fountain, the combination with a basin having a drain passage, spraying means supported above the basin for directing water toward the outer portion of the basin, said drain passage including a fitting having a pipe mounted thereon and extending up through the drain passage to a position above the top of the basin to form an annular drain passage, and a fresh water supply connection for said spraying means including a conduit supported from an exposed wall of said fitting and extending through said pipe and spaced therefrom by an air space.

4. In a wash fountain, the combination with a basin having a drain passage, spraying means supported above the basin for directing water toward the outer portion of the basin, said drain passage including a fitting having a pipe mounted therein and a trap provided with a vent passage, and a fresh water supply connection for said spraying means between said vent passage and said first named pipe and spaced by an air space from said first named pipe.

5. In a wash fountain, the combination with a basin having a drain passage, spraying means supported above the basin for directing water toward the outer portion of the basin, said drain passage including a fitting having a pipe mounted therein and a trap provided with a vent passage, and a fresh water supply connection for said spraying means between said vent passage and said first named pipe and separated by air spaces from said pipes.

6. In a wash fountain, the combination with a basin having a drain passage, spraying means supported above the basin for directing water toward the outer portion of the basin, a pipe ex-

tending upwardly through said drain passage and to a position above the basin, concentric fresh water inlet pipes extending through said first named pipe and spaced therefrom by an air space.

5 7. In a wash fountain, the combination with a basin having a drain passage, spraying means supported above the basin for directing water toward the outer portion of the basin, a pipe extending upwardly through said drain passage and to a position above the basin, concentric fresh water inlet pipes extending through said first named pipe and spaced therefrom by an air space, and a manifold connecting said inlet pipes and mounted on a part of said drain passage.

10 8. In a wash fountain, the combination with a basin having a drain passage, spraying means supported above the basin for directing water toward the outer portion of the basin, a pipe extending upwardly through said drain passage and to a position above the basin, said drain passage including a trap and a vent pipe extending upwardly from said trap and through said first named pipe; and a pipe concentric with said vent pipe and secured thereto at its lower end to form an annular upwardly extending fresh water passage projecting through said drain passage but completely separated from the waste water therein.

15 9. In a wash fountain, the combination with a basin having a drain passage, spraying means supported above the basin for directing water toward the outer portion of the basin, a pipe

extending upwardly through said drain passage and to a position above the basin, said drain passage including a trap and a vent pipe extending upwardly from said trap and through said first named pipe, and concentric fresh water inlet pipes surrounding a portion of said vent pipe and extending through said first named pipe and spaced therefrom by an air space.

20 10. In a wash fountain, the combination with a basin having a drain passage including a fitting having a chamber at one end and a passage curving laterally from said chamber to a lower end having an axis aligned with that of said chamber, a pipe mounted on the bottom wall of said chamber and projecting through said drain passage, said curved passage providing an open space with an exterior boss on said passage adjacent said open space, and a fresh water inlet pipe for said fountain, separate from said fitting, and mounted on said boss and extending through said pipe and spaced therefrom by an air space.

25 11. In a wash fountain, the combination with a basin having a drain passage, spraying means supported above the basin for directing water toward the outer portion of the basin, a fresh water supply connection for said spraying means including a conduit extending up through said drain passage, and spaced conduit means for separating said fresh water conduit from the water in said drain passage and providing a passage for any leakage from said drain passage direct to atmosphere.

30 HERMAN E. HEINE.
